Fig. I

This technical drawing illustrates a complex mechanical assembly, possibly a gear or sprocket. The central feature is a large gear labeled '9807' in large, bold numerals. Surrounding this central gear are numerous other components, each labeled with a unique number. These include: '108 110' at the top left; '130 70 64 18' in the upper right; '10 22' at the top right; '26 48 14' in the upper right; '30' on the far left; '3 2 1' on the left side; '5' on the far left; '28' at the bottom left; '52' at the bottom center; '90' at the bottom center; '84' at the bottom right; '20' at the bottom right; '16' on the right side; and '52' on the far right. The assembly is depicted with various line patterns: solid lines for main structural elements, dashed lines for internal features, and hatching for different material types or sections. The overall design is intricate, with many small parts and sub-components.

COUNTING MECHANISM

Harvey N. Bliss, Windsor, Conn., assignor to
Veeder-Root Incorporated, Hartford, Conn., a
corporation of Connecticut

Application January 29, 1941, Serial No. 376,501

8 Claims. (Cl. 235—131)

The present invention relates to counters and more particularly to counters of the type comprising a plurality of successively higher order wheels and wherein the lowest order wheel is advanced step by step by ratchet drive means and the movement of the lowest order wheel is successively carried to the wheels of higher order through suitable transfer mechanism.

In counters of this construction the order or numeral wheels are freely rotatable on a supporting shaft, and heretofore, upon rapid rotation of the lowest order wheel in a counting direction, it tends to store up inertia and overthrow a complete step or numeral, resulting in an increased and inaccurate final count.

An object of the present invention is to provide a counter overcoming the aforementioned objections by including means for preventing overthrow of the lowest order wheel during a counting operation by positively limiting it to a step by step advancement. Inasmuch as the higher order wheels will only advance after a predetermined advance of the lowest order wheel, by controlling the lowest order wheel a correct count is assured.

A still further object is a counter of the above-indicated type which is characterized by its simplicity of construction, ease and economy in assembly and manufacture, and accuracy of operation.

Other objects will be in part obvious and in part pointed out more in detail hereinafter.

The invention accordingly consists in the features of construction, combination of elements, and arrangement of parts which will be exemplified in the construction hereafter set forth and the scope of the application of which will be indicated in the appended claims.

In the accompanying drawings:

Figure 1 is a plan view of a counter embodying the invention herein with a portion of the casing broken away to show the drive means and adjacent order wheel;

Fig. 2 is a front view with the casing in section to show the drive means;

Fig. 3 is an end view of the drive means as seen with the right-hand end of the casing removed;

Fig. 4 is a plan view of the drive means and adjacent order wheels with the parts partially in section;

Fig. 5 is an end view similar to Fig. 3 and with portions of the drive means removed to show the non-back-up holding means;

Fig. 6 is a reverse view of the portion of the drive means shown in Fig. 5;

Fig. 7 is an end view of the drive means showing same in one of its extreme positions;

Fig. 8 is a view similar to Fig. 7 showing the drive means in the other of its extreme positions;

Figs. 9 to 11, inclusive, are detail views of the numeral wheels; and

Fig. 12 is a view showing the relative positions of the drive means ratchet wheels and drive pawls upon tendency of the drive means to overthrow.

Referring to the drawings, the counting unit comprises generally a casing 10 in which there is housed indicating means 12 comprising a plurality of successively higher order numeral wheels 11a to 11e rotatably mounted on a reset shaft 14 journaled in the casing 10. There is further journaled in the casing a drive shaft 16 adapted upon oscillation to operate a ratchet drive means 18 for imparting step by step advancement in a counting direction to the lowest order wheel of the indicating means.

More particularly, the casing 10 comprises a base plate 20 having an integral, inverted U-shaped supporting frame 22 and removable side closures 24. As indicated, the supporting frame 22 includes vertical legs 26 positioned adjacent the ends of the base plate and centrally of the side edges and having their upper ends interconnected by a top cross member 28. The cross member 28 has cut centrally thereof a window 30 whereby the indicating means 12 may be read.

To cooperate with the base plate 20 and frame 22, the side closures 24 are of mutilated box-like structures having a side member 32, top member 34, and end members 36. The closures 24 are of such size that the inner edges of the side and top members abut against the U frame 22, whereas the bottom edges of the side and end members rest on the base 20. To accurately align and position the side closures on the base, the upper face of the closure top member 34 terminates in a corner recess 38 to provide a projecting lip 40 receivable beneath the top cross member 28 and the vertical legs 26 of the frame 22 having inner corner recesses 42 into which the forward ends of the closure end plates may extend. The inner face of each closure side member 32 carries an arm 44 extending inwardly from its lower edge and positioned intermediate of the ends thereof; the arm 44 being provided at its inner end with a threaded opening alignable with an opening in the base plate 20, whereby upon the insertion of a suitable screw 46 the side

closures will be rigidly secured to the base and the entire casing completely assembled as a unit.

The central U frame 22 further functions as a main support for the indicating and drive means, and for this purpose legs 26 are provided with aligned openings 48 in which the counter numeral wheel supporting and reset shaft 14 is journaled. Below and in vertical alignment with the openings 48, the leg members 26 are provided with a second set of aligned openings 52 in which the drive means operating shaft 16 is journaled; this shaft being of such length that it extends outwardly and through the left leg 26, whereby it may be connected by suitable linkage to the mechanism from which the count is to be taken. The reset shaft 14 not only supports the indicating means 12, but cooperates with drive shaft 16 to support the drive means 18, and both the drive means and the numeral wheels are positioned between and held against longitudinal movement by the vertical legs 26, with the drive means mounted adjacent the lowest order wheel 11a.

Referring now to the ratchet drive means 18, it includes a hub 58 rotatably mounted on the reset shaft 14 and having a pair of diametrically opposite lugs 60 extending laterally toward and receivable within recesses 62 provided in the adjacent face of the lowest order wheel 11a, whereby, upon rotation of the hub, the wheel will be simultaneously rotated. Mounted on the periphery of the hub 58 is a ratchet wheel 64 having a plurality of substantially square-cut teeth 66 spaced by generally square-cut recesses 68 which is to say the wheel 64 has circumferentially spaced apart recesses or notches 68 the leading and trailing edges of which are generally radially disposed. This ratchet wheel is integral with the hub and constitutes a driving member for the hub and the lowest order wheel.

Also mounted on the hub 58 adjacent the ratchet wheel 64 is a second ratchet wheel 70; this second ratchet wheel being freely rotatable on the hub 58. The ratchet wheel 70 has circumferentially spaced apart triangularly shaped recesses or notches 76 the leading edges 76 of which are generally radially disposed and the trailing edges 75 of which are inclined outwardly and rearwardly. More particularly, in the present instance, the ratchet wheel 70 has a plurality of teeth each comprising a square portion 73 equal in size and number to the teeth 66 of the ratchet wheel 64 and a triangular portion 74 having a camming incline 75 extending from the base of the vertical rise 76 of one square portion to the peripheral edge of the next succeeding square portion. With the ratchet wheel so constructed, when the teeth of ratchet wheel 64 are in alignment with the square portions of the teeth of ratchet wheel 70, the camming incline 75 also extends from the base of one tooth of ratchet wheel 64 to the peripheral edge of the next succeeding tooth and functions, as will hereinafter be apparent, as a release for the ratchet wheel driving pawl 78.

In order to cooperate with the ratchet wheels 64 and 70, the driving pawl 78 carries at one end a substantially square-cut tooth 79 and is pivoted at its opposite end on an arm 80 pivotally mounted on the reset shaft 14. The pawl 78 is normally urged into engagement with the ratchet wheels 64 and 70 by a spring 82 fixed at one end to the arm 80 and having its other end biased against the free end of the pawl 78. As best seen in Fig. 4, the end width of tooth 79 is such that

it straddles both the ratchet wheels, and, as best seen in Fig. 3, its side width is less than the spacing between the square teeth of ratchet wheel 64, whereby the tooth will normally rest on the camming incline 75 of ratchet wheel 70 but within the peripheral edge of ratchet wheel 64. With this arrangement, upon pivoting arm 80 in a counterclockwise direction, the drive pawl 78 will advance both ratchet wheels, whereas upon reverse pivoting of arm 80 the pawl will be cammed out of the recess between the ratchet wheel teeth by the cammed incline 75 of the wheel 70; the wheel 70 being held against clockwise rotation by the non-back-up pawl 92 subsequently described. During the registering operation, the arm is oscillated about the reset shaft 14 by the drive shaft 16 acting through a toggle 84. The toggle has a long link 88 (see Figs. 3, 7, and 8) fixed to the drive shaft by a pin 90, and a short link 86 the opposite ends of which are respectively and pivotally connected to the long link 88 and the arm 80.

With this construction, upon oscillation of the drive shaft 16 the toggle will be successively straightened out and then broken, whereupon arm 80 will be pivoted on shaft 14 and the drive pawl 78 operated alternately in a counting and non-counting direction.

Also cooperating with the ratchet wheels 64 and 70 is a non-back-up pawl 92 terminating at its free end in a ratchet wheel engaging tooth 93 and pivotally mounted at its opposite end on a transverse shaft 94 carried by spaced standards 96 extending vertically from the base plate 28. The pawl 92 is normally urged into engagement with the ratchet wheels by a coiled spring 98 mounted on the shaft 94 and having one end fixed behind the standard 96 and the other beneath the pawl 92 beyond the pivot point. The tooth 93 of the non-back-up pawl, in like manner to the tooth 79 of the drive pawl, has an end width such that the pawl straddles both of the ratchet wheels and a side width such that the tooth normally rests on the camming incline 75, whereby, upon advance of the ratchet wheels in a counting direction, the non-back-up pawl will be cammed out of holding engagement.

The drive means not only operates the counter in the manner heretofore described, but during a driving operation positively prevents overthrow of the lowest order wheel. As will be apparent, when the drive pawl 78 is moved in a direction to drive the counter, the spring 82 positively urges the square tooth 79 of the pawl into a square recess between successive teeth of the ratchet wheel 64 and the forward edge of the tooth 79 engages against the leading edge of the notch or recess in which the tooth is engaged. If at the completion of a pawl stroke ratchet wheel 64 tends to overthrow, the trailing edge of the notch or recess 68 in which the tooth 79 is engaged will engage and interlock against the rear radially extending edge of the drive pawl tooth 79 to thus retain ratchet wheel 64 against further turning (see Fig. 12). Inasmuch as ratchet wheel 64 is positively connected to the lowest order wheel, the lowest order wheel is likewise held against overthrow. The tendency to overthrow will not, however, be transmitted to the lighter ratchet wheel 70, for the latter, being loosely mounted on the shaft, will be held in relatively fixed position by the strength of the drive and retaining pawl springs 82 and 96; these springs overcoming such inertia as may have been built up within the

ratchet wheel 78. It is likewise apparent that the aforementioned action will result if an attempt is made to overthrow the lowest numeral wheel relative to the drive means and without operating the latter. Thus the pawl 78 and ratchet wheel 68 are normally interlocked, preventing rotation of the ratchet wheel relative to the pawl, except when the latter is positively released as the pawl 78 is moved in a non-counting direction.

Upon reverse movement of the drive means, the drive pawl will return ratchet wheel 64 until it abuts the non-back-up pawl 92, whereupon the pawl will then ride up the incline 78 and be released from engagement until aligned with the next successive recess.

Referring more specifically to the drive means, it is so made as to include an overtravel to eliminate fine adjustment between the linkage between the means from which the count is to be taken and the drive shaft 16. To accomplish this, the lower end of the long toggle link 88 terminates in spaced stops 100 and 102 respectively adapted to abut at the limit of each stroke against stops 104 and 106 provided integral with the base plate 20. In this manner, the throw required for a return stroke of the pawl 78 may be increased from a minimum, where the toggle link is in the position shown in Fig. 3, to the maximum shown in Fig. 7 and, for an operating stroke, the throw may be increased from the point where the center line of the links of the toggle are in alignment to the maximum position shown in Fig. 8 where the toggle is broken to the other side of center.

As the counter shown is of the reset type, there is utilized counting wheels 11a to 11e of the type shown in Figs. 9 to 11, inclusive, which wheels are preferably made of plastic material. As seen, each order wheel comprises a wheel member 103 having a hub 105 carrying a radially extending flange 107 supporting at its peripheral edge a laterally extending flange 108 upon which the indicia zero to nine may be provided. Adjacent the indicia carrying portion of the flange 108 the flange is reduced to provide a locking shoulder 110 having a single notch 112 in alignment with a two-tooth driving gear 114. In addition, the inner face of the flange 107 is provided with a recess 118 terminating at one end in a rounded portion 120 for receiving the rounded base 122 of a reset pawl 124. The free end of the pawl is normally pivoted through a slot 123 in the hub 105 and into contact with the reset shaft 14 by a U-shaped spring 126 disposed between the pawl and the base of the recess 118. Cooperating with the wheel member 103 of each order wheel unit is a driven member 128 rotatably mounted on the hub 105.

The driven member 128 includes a twenty-tooth driven gear 138 of substantially the same diameter as the wheel and a disk portion 132 which fits within the annular cavity defined by the lateral flange 108 and the hub 105. The inner face of the disk portion 132 is formed with a pair of parallel guideways 134 each disposed at right angles to a diameter of the driven member so that the grooves are located on chords equally spaced to opposite sides of the center. The grooves extend entirely across the face of the disk and are provided with spaced lugs 136 symmetrically positioned to either side of a diameter at right angles to the groove. Located within each groove is a driving pawl 138 which, in the embodiment illustrated, comprises a metal stamping bent to substantially C form to provide opposed nose portions 139 and 141, whereby it may be readily in-

serted into the groove with the nose portions disposed to opposite sides of the left lug 136 (as viewed in Fig. 9). When so positioned, there may be inserted between the inner nose 141 of the pawl and the opposite lug a spring 140 for normally urging the pawl outwardly of the groove, whereupon the outer nose 139 will engage suitable teeth 143 formed on the inner face of the flange 108 and establish a driving connection between the driven member 128 and the numeral wheel.

With this construction, the pawl 138 may be located to project from either side of the groove, depending upon the direction in which the wheel is to be rotated. In order to maintain the reset pawl 124 within the recess 118 and the driving pawls 138 within the grooves, there is also mounted on the hub intermediate of the driven member and the numeral wheel a dividing disk 142.

The face of the driven member 128 also includes the recesses 62 for receiving the laterally extending lugs 60 of the hub 58, whereby when the latter is operated the driven member will be rotated simultaneously therewith and the pawls 138 cause simultaneous rotation of the wheel member 103 of lowest order. In order to transfer the rotation from a wheel of lower order to a wheel of higher order, there is arranged between each successive pair of wheels a transfer pinion 144 mounted on shaft 94. The pinion 144 is of usual construction having alternate long and short teeth cooperating with the locking disk 110 and two tooth gear 114 of a wheel of lower order and twenty tooth gear of the wheel of next higher order to perform transfer operations common to this type of counters.

In order to cooperate with the reset pawl 124 of the numeral wheels, the reset shaft 14 is provided with a V-shaped notch 146 whereby when the reset shaft is rotated in a counterclockwise direction the end of the pawl will be urged into the notch, and thereafter the numeral wheel will rotate with the shaft and relative to the driven member 128. To conveniently accomplish resetting, the reset shaft extends through the right vertical leg 26 of the casing and carries on its outer end a suitable manual control knob 148.

Although the counter has been shown as utilizing wheels which may be reset, it is obvious that the drive means could be readily utilized with any type of counter wheels, and, also, that the counter could utilize any number of numeral wheels, depending upon the total registration ultimately desired.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. In a counter, a numeral wheel, drive means therefor comprising a first ratchet wheel connected to said numeral wheel so as to rotate therewith, said first ratchet wheel having square cut teeth spaced by square recesses, a second

ratchet wheel mounted adjacent said first ratchet wheel and freely movable relative thereto, said second ratchet wheel having teeth alignable with the teeth of said first ratchet wheel and provided with cammed inclines extending from the base of one tooth upwardly to the top of the next tooth and alignable with the recesses of said first ratchet wheel, means for oscillating said pawl to simultaneously advance both of said ratchet wheels in a counting direction, and means for restraining both of said ratchet wheels against movement in a non-counting direction, whereby upon reverse oscillation of the pawl the camming incline of the second ratchet wheel will release the pawl out of the recess of the first ratchet wheel.

2. In a counter, a numeral wheel, a ratchet drive therefor, said drive means including one ratchet wheel connected to the numeral wheel so as to rotate therewith and a second ratchet wheel freely movable relative to said first ratchet wheel, a drive pawl for engaging both said ratchet wheels, interengaging means on said first ratchet wheel and said drive pawl for interlocking when said ratchet wheel is operated in a counting direction, and means on said second ratchet wheel cooperating with said pawl for releasing said interlocking parts when the pawl is operated in a reverse direction, and means restraining movement of said ratchet wheels in a reverse direction upon reverse movement of the pawl.

3. In a counter, a shaft, a numeral wheel rotatably mounted on the shaft, a ratchet wheel rotatably mounted on the shaft and connected to said numeral wheel so as to rotate therewith, a second ratchet wheel rotatable relative to said shaft and said first ratchet wheel, a drive pawl for engaging both said ratchet wheels, interengaging means on said first ratchet wheel and said drive pawl for interlocking when said ratchet wheel is operated in a counting direction, whereby said numeral wheel cannot be overthrown, and means on said second ratchet wheel cooperating with said pawl for releasing said interengaging means when the pawl is operated in a reverse direction.

4. In a counter, a numeral wheel, drive means therefor including a ratchet wheel connected to said numeral wheel so as to rotate therewith, said ratchet wheel being provided with square cut teeth spaced by square recesses, a second ratchet wheel positioned adjacent said first ratchet wheel and freely rotatable relative to said first ratchet wheel, said second ratchet wheel being provided with square cut teeth and cammed inclines leading from the base of one tooth upwardly to the top of the next successive tooth, means normally holding said ratchet wheels with the square cut teeth in alignment whereby the inclines of the second ratchet wheel will be aligned with the spaced square recesses of the first ratchet wheel, a driving pawl, said driving pawl being provided with a square cut tooth engaging both of said ratchet wheels, and means for oscillating said driving pawl.

5. In a counter, a numeral wheel, drive means therefor comprising a ratchet wheel connected to said numeral wheel so as to rotate therewith, said ratchet wheel having circumferentially

spaced recesses provided with substantially radially disposed leading and trailing edges, a pawl mounted for oscillatory movement generally tangentially of said ratchet wheel and for pivotal movement generally radially thereof, said pawl having a tooth adapted to successively engage in said recesses upon oscillation of said pawl, said tooth having generally radially extending forward and rear edges adapted to respectively interlock with the leading and trailing edges of the notches, means for oscillating said pawl, means for restraining said ratchet wheel against movement when said pawl is moved in a non-counting direction, and means for pivotally moving said pawl outwardly of said ratchet wheel to release the tooth thereof from said recesses after each oscillatory movement of said pawl in a driving direction.

6. In a counter, a numeral wheel, a ratchet wheel connected to said numeral wheel so as to rotate therewith and having notches, an oscillatory and pivotal pawl having a tooth engageable in said notches, said notches and pawl being generally square-cut for preventing overthrow of said wheels when the same are operated in a counting direction, drive means for oscillating said pawl to advance said wheels with a step by step movement, and means for moving the pawl outwardly to release the tooth thereof from the notches of the ratchet wheel after each completion of an oscillation of the pawl in a driving direction.

7. In a counter, a numeral wheel, a first ratchet wheel connected to said numeral wheel so as to rotate therewith, said ratchet wheel having circumferentially spaced recesses provided with substantially radially disposed leading and trailing edges, a second ratchet wheel mounted adjacent said first ratchet wheel and freely rotatable relative thereto, said second ratchet wheel having circumferentially spaced recesses each provided with a substantially radially disposed leading edge and an outwardly and rearwardly inclined trailing edge, a pawl mounted for oscillatory movement generally tangentially of said ratchet wheels and for pivotal movement generally radially thereof, said pawl having a tooth engageable in the recesses of both of said ratchet wheels and provided with generally radially extending leading and trailing edges, means for oscillating said pawl, and means for restraining said ratchet wheels against movement when said pawl is moved in a non-counting direction.

8. In a counter, a numeral wheel, drive means therefor including a ratchet wheel connected to said numeral wheel so as to rotate therewith, said ratchet wheel having generally square cut teeth spaced by generally square recesses, a second ratchet wheel positioned adjacent said first ratchet wheel and freely rotatable relative thereto, said second ratchet wheel having notches provided with a generally radially leading edge and a rearwardly and outwardly inclined trailing edge constituting cams, a driving pawl supported for oscillatory movement and for pivotal movement, said pawl having a generally square cut tooth engageable in the notches of both of said ratchet wheels, and a pivoted non-back-up pawl having a tooth engageable in the notches of both of said ratchet wheels.

HARVEY N. BLISS.
